UNITED STATES PATENT OFFICE.

JOHN W. DARLEY, JR., OF BALTIMORE, MARYLAND, ASSIGNOR TO THE UNIVERSAL STEEL PACKAGE CO., A CORPORATION OF DELAWARE.

DESIGN FOR A METALLIC BARREL.

50,295.

Specification for Design.

Patented Feb. 13, 1917.

Application filed October 21, 1915. Serial No. 57,200. Term of patent 14 years.

To all whom it may concern:

Be it known that I, JOHN W. DARLEY, Jr., a citizen of the United States, residing at Baltimore, in the State of Maryland, have invented a new, original, and ornamental Design for Metallic Barrels, of which the following is a specification, reference being had to the accompanying drawing, forming part thereof.

The figure is a perspective view of a metallic barrel showing my new design.

I claim:

The ornamental design for a metallic barrel as shown.

In testimony whereof, I affix my signature.

JOHN W. DARLEY, JR.
